[57] CLAIM

The ornamental design for a seat, as shown and described.

DESCRIPTION

FIG. 1 is a perspective view of a first embodiment of a seat
showing my new design;

FIG. 2 is a front elevational view thereof;

FIG. 3 is a top plan view thereof;

FIG. 4 is a right side view thereof, the opposite side being
a mirror image of the side shown;

FIG. 5 is a rear elevational view thereof; and,

FIG. 6 is a perspective view of a second embodiment of the
seat, the side not shown is a mirror image of that shown.

The rear view for FIG. 6 is like that shown in FIG. 5, the
only difference being a matter of length.
